UNITED STATES PATENT OFFICE

2,006,588

TOBACCO CAN

Henrietta Ehret, St. Louis, Mo.

Application July 9, 1934, Serial No. 734,393

4 Claims. (Cl. 221—11)

My invention is an improvement in tobacco cans or containers.

Manufacturers of smoking tobacco put the latter on the market in containers small enough to be conveniently carried in the user's pockets but ordinarily these containers are not provided with means to direct the discharge of the material.

The object of my invention is to provide a novel container having a relatively large cover movable to permit the container to be filled and provided with means forming part of said cover to control the direction of discharge of the material as it is withdrawn from the container.

In the drawing;
Fig. 1 is a perspective view of the invention.
Fig. 2 is a vertical sectional view thereof and
Fig. 3 is a perspective view showing the device in a pouring position.

The dispensing device comprises a body 10 made up of walls 11 and a bottom member 12 rigidly secured thereto. A cover 13 is hinged to one wall 11 and is made up of a main closure member 14 and a pouring spout or auxiliary cover 15. Member 14 is provided with flanges 16 and a recess 17 extending inwardly from one edge. Spout 15 normally closes said recess and comprises a central portion 18 and wings 19, each of which is provided with a flange 20, extending outwardly from the central plane of the spout and arranged to engage the inner wall of member 14 to limit movement of spout 15. Portion 18 is extended beyond wings 19 to provide a tip 21.

A pair of tabs 22 extends from one wall 11, a tab 14 extends from pouring spout 15 and a pair of tabs 25 extends from closure member 14. These tabs extend around a hinge pintle 26, which is secured rigidly to the tab 24 or to either pair 22 or 25. In the preferred form, tab 24 is received in the space between tabs 22, which in turn are received in the space between tabs 25.

In use, the entire cover 13 may be opened to permit the body member to be filled, after which the cover is closed. When the user desires to fill his pipe, the spout may be swung around the hinge pintle and used to direct tobacco into the pipe bowl as shown in Fig. 3. While the device is particularly useful as a pocket receptacle for tobacco, it may obviously be made of suitable proportions and changed somewhat to increase its

field of usefulness as a dispenser of granular materials. I, therefore, do not wish to be restricted to the exact form shown or restricted beyond the terms of the appended claims.

I claim as my invention

1. A dispensing device comprising a hollow body member, having an open end; a cover for closing the same; and a hinge structure connecting said cover to said body member; said cover comprising a main closure member, provided with a recess extending inwardly from one edge thereof, and an auxiliary closure member forming a spout and arranged to close said recess; and said hinge structure comprising tab means, extending in parallel planes from said body member and from said closure members, and a common pintle for said closure members, encircled by said tab means and secured rigidly to the tab means extending from one of said members.

2. A device of the type described in claim 1, in which the tab means carried by the main closure member are arranged on opposite sides of the recess therein and define a space receiving the tab means of the other members.

3. A device of the type described in claim 1, in which the tab means of the body member and main closure member define spaces receiving the tab means extending respectively from the auxiliary closure member and from the body member.

4. In a dispensing device, the combination with a hollow body member, having an open end; of a cover, comprising a main closure member and an auxiliary closure member; and a single hinge pintle connected to each of said members to join an edge of the cover to the adjacent end of one wall of the body member; said main closure member having a recess extending inwardly from said edge and said auxiliary member comprising a central portion adapted to close said recess, parallel wing members and flanges extending therefrom and arranged to cooperate with the main closure member to restrict movement of the auxiliary closure member, said wing members being arranged to form with the central portion of the auxiliary closure member a pouring spout to direct the movement of material poured through said recess.

HENRIETTA EHRET.
